CLAIM

The ornamental design for a modular furniture kit substantially as shown and described.

DESCRIPTION

FIG. 1 is a front view of a kit for a modular furniture comprising a pair of brackets and central component;

FIG. 2 is a rear view of the kit of FIG. 1;

FIG. 3 is a top view of the kit of FIG. 1;

FIG. 4 is a bottom view of the kit of FIG. 1;

FIG. 5 is a left view of the kit of FIG. 1;

FIG. 6 is a right view of the kit of FIG. 1;

FIG. 7 is a left perspective view of the kit of FIG. 1;

FIG. 8 is a right perspective view of the kit of FIG. 1; and,

FIG. 9 is a perspective view of the kit of FIG. 1, shown in a state of use.

The broken lines shown in the drawings are for illustrative purposes only and form no part of the claimed design.
